Primary Examiner — Selina Sikder(74) *Attorney, Agent, or Firm* — Buchanan, Ingersoll & Rooney PC(57) **CLAIM**

The ornamental design for a cam switch, as shown and described.

DESCRIPTION

FIG. 1 is a perspective view of a cam switch showing a first embodiment of our new design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a top plan view thereof.

FIG. 7 is a bottom plan view thereof.

FIG. 8 is a perspective view of a cam switch showing a second embodiment of our new design.

FIG. 9 is a front elevational view thereof.

FIG. 10 is a rear elevational view thereof.

FIG. 11 is a left side elevational view thereof.

FIG. 12 is a right side elevational view thereof.

FIG. 13 is a top plan view thereof; and,

FIG. 14 is a bottom plan view thereof.

The broken line showing of the cam switch is for the purpose of illustrating environmental structure and forms no part of the claimed design.
